UNITED STATES PATENT OFFICE.

CHARLES J. JOLIDON, OF HARTFORD, CONNECTICUT.

FIREARM.

1,382,197.

Specification of Letters Patent. Patented June 21, 1921.

Application filed July 16, 1917, Serial No. 180,705. Renewed November 23, 1920. Serial No. 426,107.

To all whom it may concern:

Be it known that I, CHARLES J. JOLIDON, a citizen of the United States, residing at Hartford, in the county of Hartford and 5 State of Connecticut, have invented certain new and useful Improvements in Firearms, of which the following is a specification.

This invention relates to firearms. A firearm involving the invention can be used in a 10 variety of different ways; for illustration as a pistol, although as may be inferred the invention is not restricted in this particular. One of the primary purposes that I have in view is the radical simplification of 15 a firearm which I accomplish by the elimination of a number of parts now essential to the proper action thereof.

In the drawings accompanying and forming part of the present specification I show 20 in detail one of the several convenient forms of embodiment of the invention which to enable those skilled in the art to practice the same will be set forth fully in the following description. I do not, as will be clear, restrict myself to this disclosure; I may depart therefrom materially in many respects 25 within the scope of the invention defined by the claims following said description.

Referring to said drawings:

30 Figure 1 is a side elevation of practically the major portion of a firearm involving the invention.

Fig. 2 is a longitudinal sectional side view of the same, showing the parts in their forward or firing position.

Fig. 3 is a like view with the parts in their retracted positions.

Fig. 4 is a front elevation.

Figs. 5 and 6 are cross sections on the line 40 5-6 of Fig. 2, looking in the direction of the arrow, and with the parts in positions corresponding relatively to Figs. 2 and 3.

Figs. 7 and 8 are horizontal sections on the line 7-8 of Fig. 3, looking in the direction 45 of the arrow applied to said line and with the parts in positions corresponding respectively to Figs. 2 and 3.

Figs. 9 and 10 are cross sections on the line 9-10 of Fig. 1, looking in the direction of 50 the arrow and with the parts in different positions.

Figs. 11 and 12 are horizontal sections on the line 11-12 of Fig. 10, looking in the direction of the arrow touching said line and 55 with the parts in positions corresponding respectively with Figs. 9 and 10.

Fig. 13 is a cross section on the line 13-13

of Fig. 12, looking in the direction of the arrow applied to said line but without the breech-slide or bolt carrier applied.

60

Fig. 14 is a practically similar view, showing, however, the breech-slide on the frame.

Fig. 15 is a longitudinal section on the line 15-15 of Fig. 11, looking in the direction of the arrow, showing the breech-slide in position.

65

Fig. 16 is a practically similar view, the breech-slide being shown as introduced and as meeting the abutment which prevents its sliding onto the frame from the front.

70

Like characters refer to like parts throughout the several views, which it will be apparent are on slightly different scales.

On the recoil of the barrel with the breech-bolt, the barrel has an independent movement given to it, during which it is unlocked from the breech-bolt and arrested in its retractive movement, although the breech-bolt continues its recoil until the breech is fully opened. During this opening 80 of the breech-bolt, energy is stored in a spring, the reaction of which is utilized to effect the return of the breech-bolt, and as an incident the return of the barrel both to primary or firing relations. Among the fundamental objects I have in view are the provision of means of an exceedingly simple nature by which the barrel can have the necessary limited retractive or rearward movement with the breech-bolt and return 85 with the breech-bolt to initial position during the final part of the forward or advance movement of the breech-bolt. Another motive I have in view is the association of the "breech-slide" or "bolt-carrier" as it is variously known, with the frame in such manner as to interfere in no wise with the requisite motion of the breech-slide or bolt-carrier or barrel for that matter. The invention is, therefore, for the purpose of showing its 90 utility and simplicity, incorporated in an automatic pistol which in certain respects resembles a piece now in every-day use. As will be understood, however, the invention is not limited in this particular arm, for some 95 and all of its features may be embodied in an entirely different type of arm.

The pistol shown involves in its organization, three principal elements such as a frame as 2, a barrel as 3 and a breech-slide 110 or bolt-carrier as 4. This breech-slide or bolt-carrier 4 is slidable rearwardly and forwardly upon the frame 2 under the action for instance of the recoil and of the reaction-

spring respectively. The frame 2 is furnished with the usual grip within which is the seat 6 for the detachable cartridge-magazine in which cartridges are superimposed upon a spring-follower, by which they are advanced into the receiver in the frame. In the rear of the grip is the hammer and other elements of the firing and safety mechanisms, while the trigger 7 is within the trigger-guard 8. The parts already described are, except as hereinafter set forth, practically the same in construction and mode of operation as corresponding elements found in an old pistol to which allusion has already been made. The exceptions, as will be understood, are striking.

The frame has at the front a semi-circular extension 9, the upper edge 10 of which is as shown, horizontal and is below the horizontal upper portion of the body 11 of the frame. The upper portion of the body 11 has the lateral transversely alined longitudinally-extending grooves 12, the lower walls of which are as shown in the plane of the upper edge of the side portions of the semi-tubular extension 9. It is proper to refer at this point to the fact that the breech-slide or bolt-carrier is not assembled upon the frame by a sliding motion from the front. This in fact is one of the several important and striking differences between the present firearm and what is old. In fact I prefer to provide as I will hereinafter point out, means of a positive nature, to prevent the breech-slide or its equivalent from being slid onto the frame from the front of the latter.

The upstanding portion of the body 11 is perpendicularly slotted as at 13, the ends of the slot being open. The upper open end of this slot is coincident with the upper surface of the body 11, the lower end of the slot as will be understood cutting one of the grooves or channels 12 or that at the left in Figs. 9 and 10 or uppermost in Figs. 11 and 12. I might note at this time that the purpose of this slot 13 is to receive a tongue or projection on the breech-slide or bolt-carrier 4 to provide for the proper assembly of these two parts.

As is usual in arms of this general type, the rear part of the breech-slide forms the breech-bolt and forward of this the breech-slide extends in the form of a partial tube as 14. At the forward end the breech-slide is provided with a smaller and pendent tube 15, which extends rearwardly a comparatively short distance, its axis being parallel with the axis of the breech-slide. The breech-slide back of this tubular portion 15 embraces and slides on the frame 2, the rear end of the pendent tubular portion 15 as will be clear on backward movement under recoil, striking the front end of the main portion 11 of the frame 2 to thus limit the recoil.

This particular point, however, does not con-

cern the invention. One of the features of the invention as will be inferred, is the way in which the breech-slide 4 is assembled with the frame 2. I have already alluded to the fact that the body 11 has lateral channels or grooves 12 and that one of these grooves is intersected by a slot as 13 open on its opposite ends. The side walls of the semi-tubular main portion of the breech-slide have co-operating grooves or channels 16, the lower edge of said main portion being beveled off for facility of assemblage as shown at 17. The grooving of the breech-slide at 16 produces the transversely alined ribs 18, one of these ribs or the one on the left in Figs. 9 and 10 and uppermost in Figs. 11 and 12 being at its rear portion removed except for a projection or tongue 19. In assembling the rib 18 on the right in Figs. 9 and 10 which is the one on the right looking toward the front of the piece, is introduced into the corresponding groove 12 as shown in Fig. 9, while the breech-slide 4 is tipped, the projection or tongue 19 at this time being above and in register with the slot 13. At this time it will be clear that the left portion of the breech-slide 4 can be tipped down to carry the tongue or projection 19 through the slot or opening 13 or until the rib 18 on the left registers with or enters the corresponding groove 12. This will seat the breech-slide 4 substantially upon the body 2, and it will, therefore be clear that the breech-slide can be moved backward or forward under recoil or reaction. To remove the breech-slide, it will be necessary to so manipulate it as to bring the projection 19 in register or coincidence with the slot 13 when the breech-slide can be tipped from off the frame in a direction opposite or reverse to that already described. When the breech-slide, however, is connected with the frame, it is free to move backward and forward during recoil and subsequent firing or otherwise, although it becomes a simple matter to dismount the parts. It will, of course, be understood that during firing and recoil the breech-slide 4 has a firm and substantial bearing upon the frame 2.

I provide means of a positive nature to prevent the breech-block or bolt carrier 4 being slid upon the frame 3 from the front of the frame either alone or with the barrel, and in this particular differ radically from an arm with which I am familiar. As will be clear the means in question may vary decidedly, although that shown for the purpose meets my conditions in a satisfactory manner and will now be described. Intersecting one of the grooves 12 or that at the left in Figs. 9 and 10 and uppermost in Figs. 11 and 12 and as shown in Figs. 13, 14, 15 and 16 and best in Fig. 13, is a depthwise-extending bore or hole 50, the upper open side of which is flush with the top surface of

the frame 2 or body 11 thereof. This bore is situated near the front of the frame as shown for instance in Figs. 11 and 12. The bore or hole 50 receives the plunger or stop 51 backed up by the spring 52 bottoming in the bore or cavity 50 and is limited in its movements by the pin 53, the spring tending constantly to advance the plunger. The pin 53 enters a channel or groove 54 cut in the adjacent and front side of the plunger 51, the lower wall of the groove or channel when the plunger is in its elevated position as shown for instance in Figs. 15 and 16 bearing against the pin 53. The plunger 51 at its upper end has angular faces 55 which converge, the result being that the breech-block 4 can be tipped on from the side as already described. The lower portion of the breech-slide has in it a slot 56, the side walls 57 of which converge upwardly and these angular walls 57 on either forward or backward movement of the breech-slide permit the necessary completion of the movement. Should the breech-slide be slid into the frame from the front it can move but an exceedingly slight distance or until the rear end of the breech-slide encounters the front of the plunger, stop or abutment 51 just above the groove 54, this part of the stop or abutment being straight, so that it becomes absolutely impossible to slide the breech-block onto the frame from the front. The breech-block during its normal recoil and return of course keeps the stop or detent 51 wholly within the lower portion of the socket or opening 50 as shown by Fig. 14.

When the breech-slide 4 is in its forward position as shown for instance by Figs. 1 and 2, it receives within its front end the bushing 20. This bushing as will be clear, does not recede or retract with the breech-slide 4 or the barrel 2, being normally fixed, although capable of removal. It comparatively closely fits within the upper front portion of the breech-slide, however, when the latter is in its forward position. Said bushing is equipped with a pendent abutment 21 which when the breech-slide is in said advanced position is disposed within the tubular extension 15 of the breech-slide and to which I have already referred. Extending rearwardly from the abutment 21 is the pin or rod 22 which lies in the channel 23 in the forward portion of the frame 2, the rear portion of the pin fitting the socket 24 in said body 11 as shown best in Fig. 2. Although it is not imperative that any means be provided for holding the pin 22 and necessarily the abutment 21 and bushing 20 in assembled relation, I prefer to provide for this purpose a key 25 which extends through a perforation 26 in the frame 2 and which lies in a groove 27 in the rear under portion of said pin 22 as shown in Figs. 1, 2 and 3. By removing the key 25,

it becomes a simple matter to dislodge the pin 22 and therefore the abutment 21. It will, therefore, be clear that this provides a simple way of removably or detachably mounting the pin 22 and therefore the bushing 20 associated therewith. The pin 22 is surrounded by the reaction spring 28, the front end of which bears against the abutment 29 of the breech-slide 4, and the rear end of which bears against the abutment or rear wall 30 of the channel 23, the front end of the channel being, of course, open to receive for sliding movement the tube 15 of the breech-slide as shown best by Fig. 2.

The barrel 3 is given after firing first a recoil movement, and then a return movement, the former being accomplished by the expansive power of the gases on firing and the latter by the spring 28 as will hereinafter appear. As I have already noted the barrel moves rearwardly with the breech-slide 4 for a certain or limited distance. During this particular rearward movement of the barrel, it is turned or rotated, and at the conclusion of this compound movement, it is automatically released from the breech-slide, so that the breech-slide can complete its recoil movement. When the recoil of the breech-slide is concluded, the breech-slide will be advanced, and after it has moved forward a certain distance, it will carry the barrel forwardly therewith, and during this latter advance of the barrel, the barrel is given a return turning or rotary movement to restore it to its primary or firing position. For securing the necessary rotary movement of the barrel 3, I prefer to provide as will herein-after appear, means on the normally fixed bushing 20 coöperative with the barrel. This means may vary decidedly. As a matter of fact I am not restricted to the use of any particular means in any particular place for securing the requisite rotary movement of the barrel, although when located at the place indicated proper results can be obtained. In the bushing 20 and as shown diametrically opposite or horizontally aligned with each other are the companion spiral grooves 31, both open at their ends. These grooves receive the complementary spiral projections 32 also obviously diametrically opposite, situated near the forward end of the barrel 3. When, therefore, the breech-slide 4 is operated under recoil, it carries the barrel therewith and owing to the association of the spiral projections or ribs 32 with the spiral grooves or channels 31, the barrel is given a turning movement sufficient to unlock it from the breech-slide, so that the breech-slide can continue its retractive movement free of the barrel. On the forward motion of the breech-slide and after it has traveled a certain distance, it engages the butt portion of the barrel and advances the

4
latter. On the forward movement of the barrel with the breech-slide, the barrel is necessarily given a return rotary movement as it moves in a forward longitudinal direction, the motion continuing until both the breech-slide and the barrel reach their initial positions as shown for example in Figs. 1 and 2. This turning of the barrel on its backward and forward movements is a very important point of the invention. It is exceedingly simple.

The rear portion 33 of the barrel is of greater diameter than the forward portion, although as will be clear the bore of the barrel is of uniform diameter throughout its length as is usual. This thickening of the rear portion of the barrel is in itself not uncommon, and gives to the barrel at the breech or rear, the requisite rigidity and strength.

On the thickened portion of the barrel 3 are two pairs of lugs 34, the lugs of the respective pairs being situated practically sixty degrees apart and being near the forward end of the thickened portion 33 of the barrel. In the breech-slide and practically near the middle part thereof are the transverse grooves 35. When the parts are in firing position as shown for instance in Figs. 1 and 2, the two pairs of lugs 34 will be in the transverse grooves 35. As a result on the recoil of the breech-slide 4 the barrel 3 will move with the breech-slide, the barrel, however, on such recoil movement of the breech-slide turning as I have already pointed out, so that the two pairs of lugs 34 will traverse the transverse grooves 35. Opening into the transverse grooves are the longitudinal and forwardly extending channels 36 which are in parallelism. These grooves 36 are spaced a distance apart agreeing with the distance between the two pairs of lugs 34. As the barrel 3 moves rearwardly with the breech-slide, it will be understood that it is turned as I have already set forth, the turning continuing until the forward one of the respective pairs of lugs 34 is in register with or opposite the rear end of its channel 36. When this takes place the breech will thus be automatically unlocked from the barrel, so that the breech-slide can continue to recoil and during the continuation of the recoil, the pairs of lugs 34 traverse the parallel grooves 36. It will be supposed that the recoil has been completed and that the breech-slide 4 is being returned by the spring 28 as will hereinafter appear. On the forward movement of the breech-slide 4 the pairs of lugs 34 will relatively travel backward in the parallel channels 36 and until the lugs are out of said channels and opposite the transverse grooves 35. As the breech-slide continues its forward movement the barrel is given a return turning movement by reason of its described connection

with the bushing 20. During this return turning movement of the barrel, the lugs 34 will travel along the transverse grooves 35 as the barrel is turned. Owing to this the barrel is locked to and returns with the breech-slide when the breech-slide has practically concluded its forward movement. On firing, the breech-slide 4 and barrel 3 are recoiled by the gases, and as a consequence the spring 28 is compressed as shown for example in Fig. 3, the result being that there is sufficient power stored in the spring to return the breech-slide and then the barrel to firing positions.

In the body 11 of the frame is cut a seat 37 shown as rectangular and which receives a key 38 on the barrel, the front and rear walls of this seat or pocket 37 acting as stops to arrest the barrel when in the forward and backward positions. The front wall of the seat or cavity 37 is slotted out as at 39 and by turning the barrel 3 the projection or key 38 can be brought into register with the slot 39 so as to move the key through the slot in the direction indicated by the arrow 60 in Fig. 8 when it is desired to take out the barrel.

When the parts are in firing position as shown in Fig. 7, the key or projection 38 abuts against the uncut portion of the front wall of the seat or cavity 37. As the barrel moves rearward and turns in the manner already set forth, the projection 38 moves in a direction corresponding practically to the arrow 61, the result being that when the barrel completes its rearward movement, the key will be against the rear wall of the seat and diagonally opposite its first position. On forward movement of the barrel the key is revolved and advanced with a compound movement in the direction indicated by the arrow 62 in Fig. 8, so that when it reaches its primary position, it abuts against the uncut portion of the forward wall of the seat of pocket which position it is shown as occupying in said Fig. 7.

I have described hereinbefore how the breech-slide can be removed by bringing the projection 19 in register or coincidence with the slot 13. It is also clear that although said breech-slide cannot be slid onto the frame from the front of the latter, it can be slid from off the frame. In view of this situation the breech-slide can only be applied to the frame in one way, but it can be taken from the breech-slide in either of two ways.

What I claim is:

1. A firearm comprising a retractable and advanceable breech-block, a barrel co-operative with the breech-block, means for effecting the movement of the barrel with the breech-block on retractive and advancing movements thereof, a bushing fixed with respect to the breech-block and provided with

- means coöperative with the barrel for turning the same at predetermined points in said retracting and advancing movements, to first release it from and then unite it with 5 said breech-block, a pin extending rearwardly from the bushing, and a spring surrounding the pin, the spring being compressed by the breech-block on the retractive movement thereof and by reaction operating 10 against the breech-block to advance the same.
2. In a firearm a retractable and advanceable breech-block, a barrel coöperative with the breech-block, means for effecting the movement of the barrel with the breech-block 15 on retractive and advancing movements thereof, a bushing fixed with respect to the breech-block and receiving the barrel, the bushing having opposite spiral grooves and the barrel being equipped with opposite spiral projections fitting the grooves to turn the barrel on retracting and advancing movements of the breech-block to successively release and lock the barrel to the breech-block, a pin extending rearwardly from the 25 bushing, and a spring surrounding the pin, the spring being compressed by the breech-block on the retractive movement thereof and by reaction operating against the breech-block to advance the same.
3. A firearm comprising a frame, a retractable and advanceable breech block on said frame, a barrel coöperative with the breech block, means for effecting the movement of the barrel with the breech block 30 on retractive and advancing movements thereof, a rod detachably connected with the frame, and means associated with said rod for turning said barrel at predetermined points in said retractive and advancing movements to first release it from and then unite it with said breech block.
4. A firearm comprising a retractable and advanceable breech block, a barrel coöperative with the breech block, means for effecting the movement of the barrel with the breech block on retracting and advancing movements thereof, a bushing fixed with respect to the breech block, and provided 45 with means coöperative with the barrel for turning the same at predetermined points in said retracting and advancing movements to first release the barrel from and then unite it with the breech block, a pin, the bushing having an abutment to which said pin is connected and extends rearwardly, and a coiled spring surrounding the rear portion of the pin, the breech block having a tubular extension to receive and be engaged by the spring, the spring being compressed on the 55 rearward movement of the breech block and by reaction acting to advance the breech block.
5. A firearm comprising a retractable and advanceable breech block, a barrel coöperative with the breech block, means for effect- 60
- ing the movement of the barrel with the breech block on retractive and advancing movements thereof, a bushing provided with a rearwardly extending pin, the breech block having a tubular extension through which 70 said pin extends, a coiled spring around the pin, the extension having a part engageable by one end of the spring, the other end of the spring engaging the frame of the fire- 75 arm, the spring on retractive movement of the breech block being compressed and by reaction serving to return the breech block to its advanced position, the bushing being thus fixed with respect to the breech block and being provided with means to turn the 80 barrel at predetermined points in the retractive and advancing movements of the breech block to first release it from and then unite it with the breech block.
6. In a firearm a retractable and advanceable breech block, a barrel coöperative with the breech block, means for effecting the movement of the barrel with the breech block on retractive and advancing movements thereof, a stationary bushing receiving 85 the forward end of the barrel, the bushing having opposite spiral grooves and the barrel being equipped with opposite spiral projections fitting the grooves to turn the barrel on retracting and advancing movements of the breech block to successively release and lock the barrel to the breech block, the breech block having a tubular extension and the bushing having an abutment, a pin 90 fixed to the abutment and extending through said tubular extension, and a coiled spring surrounding the pin bearing at its rear against the frame of the firearm, the tubular extension having a part engaged by the forward end of the spring.
7. A firearm comprising a retractable and advanceable breech block, a barrel coöperative with the breech block, means for effecting the movement of the barrel with the breech block on retractive and advancing movements thereof, a stationary bushing provided with means for turning the barrel at predetermined points in said retractive and advancing movements to first release it from and then unite it with the 100 breech block, a pin rigid with and extending rearwardly from the bushing, the breech block having a tubular extension to receive the pin, and a coiled spring surrounding the pin and bearing respectively against said 105 tubular extension and the frame of the firearm.
8. A firearm comprising a retractable and advanceable breech block, a barrel coöperative with the breech block, means for effecting the movement of the barrel with the breech block on retractive and advancing movements thereof, a stationary bushing receiving the barrel and provided with means for turning the barrel at predetermined 110
- 125
- 130

- points in said retractive and advancing movements to first release the barrel from and then unite it with the breech block, a pin extending rearwardly from the bushing, and a coiled spring surrounding the pin and acting respectively against the breech block and the frame of the firearm.
9. In a firearm, the combination of a frame and a breech-block, the breech-block being tippable onto the frame from the side thereof to connect it therewith, and means for positively preventing the breech-block being slid onto the frame from the front thereof.
10. A firearm comprising a frame, a breech-block tippable onto the frame from the side thereof and slidable thereon when in assembled relation therewith, the frame being provided with a detent to prevent the breech-block being slid onto the frame from the front.
15. 10. A firearm comprising a frame, a breech-block tippable onto the frame from the side thereof and slidable thereon when in assembled relation therewith, the frame being provided with a detent to prevent the breech-block being slid onto the frame from the front, and permitting the withdrawal of the breech-block from the front of the frame.
20. 11. A firearm comprising a frame, a breech-block tippable onto the frame from the side thereof and slidable thereon when in assembled relation therewith, the frame being provided with a detent to prevent the breech-block being slid onto the frame from the front, and permitting the withdrawal of the breech-block from the front of the frame.
25. 12. The combination of a frame, a breech-block movable on the frame, a barrel movable with the breech-block, the frame having a rectangular cavity and the barrel having a rectangular projection at its rear end portion to enter the cavity and to limit the movement of the barrel, the cavity having an opening for the passage of the projection to thereby permit dismounting of the barrel when desired.
30. 13. A firearm comprising a frame, a retractable and advanceable breech block on said frame, a barrel coöperative with the breech block, means for effecting the movement of the barrel with the breech block on retractive and advancing movements thereof, a rod detachably connected with the frame, means connected with said rod for turning said barrel at predetermined points in said retractive and advancing movements to first
35. release it from and then unite it with said breech block, and a spring supported below the barrel and compressible by the breech block on the retractive movement thereof and reactively operating against the breech block to advance the same.
40. 14. A firearm comprising a frame, a retractable and advanceable breech block on said frame, a barrel coöperative with the breech block, means for effecting the movement of the barrel with the breech block on retractive and advancing movements thereof, a rod detachably connected with the frame, a member connected with the rod and operatively associated with the barrel, one of the
45. 65 two mentioned last parts having spiral pro-
- jecting means, and the other being spirally grooved to receive said projecting means to thereby turn the barrel at predetermined points in said retractive and advancing movements, to first release it from and then unite it with said breech block, and spring means conditioned by the breech block on the retractive movement thereof, to advance said breech block.
50. 15. A firearm comprising a frame, a retractable and advanceable breech block on said frame, a barrel coöperative with the breech block, means for effecting the movement of the barrel with the breech block on retractive and advancing movements thereof, an element detachably connected with the frame, receiving the front end of the barrel and provided with means for turning said barrel at predetermined points in said retractive and advancing movements, to first release it from and then unite it with said breech block, a rod extending from said element and having a rigid connection with the frame, and a spring around the rod and compressible by the breech block on the retractive movement thereof and reactively operating against the breech block to advance the same.
55. 16. In a firearm, the combination of a frame and a breech block, the frame having lateral transversely alined, longitudinally extending grooves, and the breech block having transversely alined ribs to fit and slide in said grooves, a spring plunger on the frame, to extend across one of the grooves of the frame and positively prevent the application of the breech block from the front of the frame, the breech block being cut away through one of its ribs to permit its registration with the plunger and thus being tipped onto the frame from the side thereof.
60. 17. In a firearm, the combination of a frame and a breech block, the frame having lateral transversely alined, longitudinally extending grooves, and the breech block having transversely alined ribs to fit and slide in said grooves, a spring plunger on the frame, to extend across one of the grooves of the frame and positively prevent the application of the breech block from the front of the frame, the breech block being cut away through one of its ribs to permit its registration with the plunger and thus being tipped onto the frame from the side thereof, the free end of the plunger being beveled on the rear side to thus permit the breech block being slid from the frame by way of the front thereof.
65. In testimony whereof I affix my signature in the presence of two witnesses.

CHARLES J. JOLIDON.
